L. E. WHITON.

PROTECTION OF SHIPS AGAINST TORPEDO ATTACK.

APPLICATION FILED JULY 22, 1913.

1,339,372.

Patented May 4, 1920.

Lucius E. Whiton
By his Attorney, M.

orneys, , Mr.

Eltonovo
Mitchell & May.

UNITED STATES PATENT OFFICE.

LUCIUS E. WHITON, OF NEW LONDON, CONNECTICUT.

PROTECTION OF SHIPS AGAINST TORPEDO ATTACK.

1,339,372.

Specification of Letters Patent.

Patented May 4, 1920.

Application filed July 22, 1918. Serial No. 246,006.

To all whom it may concern:—

Be it known that I, LUCIUS E. WHITON, a citizen of the United States of America, residing at New London, Connecticut, have invented a new and useful Protection of Ships Against Torpedo Attack, of which the following is a specification.

My present invention has for one of its important objects the provision of a means 10 of protection against torpedo attack in which it will not be necessary to have special outboard rigging for maintaining the protection at the requisite distance from the side of the ship.

Another object is to enable the placing 15 and maintenance of the protective barrier the proper distance from the side of the ship.

Another object is to provide an efficient 20 form of protection which can be readily built up and assembled from the materials ordinarily at hand.

In the carrying out of the invention, I employ, what I have termed a series of 25 steering and towing elements, arranged on edge in the water in spaced apart relation, one in advance of the other, and provide tow lines for the same, attached to the fore and aft portions of such elements, for maintaining them in substantial parallelism, 30 whereby by the adjustment of such tow lines, the angle made by the elements in respect to the towing ship may be varied to steer such elements closer to or farther away 35 from the side of the ship. These towing units are preferably arranged on divergent lines at opposite sides of the bow of the ship. A barrier or protective wall is towed from each set of such towing elements so that by 40 steering said elements inward or outward, the main protective wall may be shifted with respect to the side of the ship.

Other features and details of construction will appear as the specification proceeds.

45 In the accompanying drawing, I have illustrated more or less diagrammatically, a practical embodiment of my invention, wherein—

Figure 1, is a plan view of the invention as 50 applied to the protection of a ship, showing in dotted position, at one side of the ship, the steering elements collapsed or brought in against the side of the ship.

Fig. 2 is a view in side elevation of the 55 invention.

Figs. 3 and 4 are front and end views of

one of the float sections or units of the protective wall.

The main protective wall is designated 5, and is in the form of a barrier, floated on 60 edge at the side of the ship and made up usually of a series of sections 6, flexibly joined together as by means of the connecting loops 7.

These sections are preferably constructed 65 of inherently buoyant material such as wood, and may be constructed as shown in Figs. 3 and 4 of flat boards 8, fastened together in edge to edge relation by angle bars 9 at the bottom and battens 10 at the top. 70 These angle irons serve the additional function of weighting the lower edge of the sections and said sections may be further weighted to cause them to stand upright in the water as by securing an anchor chain 11 75 to the lower edge of the sections. This anchor chain acts also as additional means to flexibly tie the floatable sections together.

The steering sections 12 may be constructed 80 in the same way as those just described and said sections are, as most clearly shown in Fig. 1, joined in substantially parallel relation by tow lines 13, 14 attached to the fore and aft ends of the sections. The arrangement is such that the sections practically 85 overlap so as to provide a continuous barrier.

It will be evident that by relatively shifting the tow lines 13, 14 the sections may be simultaneously turned with respect to the 90 axis of the towing ship, and thereby be caused to steer outward or inward with respect to the side of the ship.

The towing chains 13—14 may be arranged in pairs as indicated most clearly 95 in Fig. 2, one chain of each pair being connected to the bottom portion of the forward float and the other chain of such pair being connected to the upper or intermediate portion of the float. It will be seen from this that by lengthening or shortening these upper and lower chains with respect to each other, the floats may be inclined vertically in either direction more or less in the water.

The towing lines are shown passed over 100 pulleys 15 supported on the bow-sprit or other forward portion 16 of the vessel. The steering of the floats may be accomplished by attaching the tow lines to a suitable windlass or windlasses but in the illustration 105 this function is accomplished by means of a chain hoist construction involving a

chain-wheel 17 operated by a hand chain 18 and serving through the usual worm gearing to turn the chain pulleys 19 which carry the hoist chains 20, such hoist chains 5 being connected to the tow lines at 21 and having turn-buckles 22 incorporated therein. The usual method of operation is to connect the tow lines of one set, say the tow lines 13, to one end of one hoist chain 10 and the tow lines (14) of the other set to the other end of the same hoist chain. It follows from this that as the hand chain is operated, the pulleys 19 will be turned and will by means of the chains 20 shift the 15 two sets of chains 13 and 14 relative to each other thereby inclining the floats inwardly or outwardly as the case may be, to cause them to steer toward or away from the side of the ship. The turn-buckles 22 enable an 20 adjustment in the length of the chains such as to incline the floats in the water in either direction from the true vertical. This is useful in case it becomes necessary to slant the floats so as to cause them to "plow" into 25 the water to off-set the lifting tendency exerted by the tow lines.

The chain hoist is shown mounted so as to be bodily adjustable forward and aft by attaching it to a cable 23 passed under a 30 pulley 24 and up over a block 25. By means of this cable it is possible to shift the chain hoist and thus advance or back the floats bodily with respect to the ship.

Instead of by chains or towing lines the 35 steering floats may be joined by means of relatively flat links 26 pivotally engaged with opposite ends of adjoining floats, these links serving to hold the floats in the spaced relation predetermined upon.

40 The main barriers 5 are attached to the steering and towing units as by means of the connection 27 which may be in the form of a chain and which chain is shown connected at 28 approximately at the center or 45 intersection of the diagonal axes of the next to the outermost float of the series, thus leaving a gap 29 for the surface water thrown up by the bow of the ship, which gap is however protected by the outermost 50 float of the series.

With the arrangement illustrated in Fig. 1, the towing units are disposed on divergent angles at opposite sides of the bow portion of the ship. Full protection is afforded for 55 the sides of the ship and the steering units at opposite sides of the ship may be trimmed to suit the water conditions at such opposite sides. The trains are preferably kept under control at the stern by means of 60 stern lines 24 attached to the rear ends of the barriers.

Fig. 1, shows in dotted lines how the floats may be collapsed in at the side of the ship and it will be evident from the preceding that by simply varying the angles

of the steering floats the barriers may be steered off to any required distance from the side of the ship, as shown as the ship gets under way and the means described provide for any required trimming to meet 70 various conditions.

What I claim is:—

1. Means for protecting ships against torpedo attack, comprising barriers floated on edge in spaced relation and disposed one 75 in advance of the other, and towing lines connecting the forward and rearward portions of such barriers in substantial parallelism, adapted when relatively displaced to simultaneously change the angles of said 80 barriers with respect to a ship protected thereby.

2. Means for protecting ships against torpedo attack, comprising a series of barriers floated on edge in spaced relation, one 85 in advance of the other at the side of a ship, towing lines from said ship connecting the barriers in substantial parallelism and means for displacing the towing lines relative to each other to thereby simultaneously shift the barriers to form different 90 angles with respect to the ship protected.

3. Means for protecting ships against torpedo attack, comprising a barrier floated on edge at the side of the ship, a series of 95 towing members comprising vanes floated on edge in spaced relation, one in advance of the other, and towing lines attached to the forward and rearward edges of the towing vanes and holding the same in substantial parallel relation, means whereby said towing lines may be relatively shifted to simultaneously change the angles of the vanes to thereby cause said vanes to veer off from or approach the sides of the ship, the 100 barrier aforesaid being attached to said vanes.

4. Means for protecting ships against torpedo attack, comprising a series of steering and towing elements floated on edge in 110 spaced apart relation and one in advance of the other, towing means attached to the forward and the rearward edge portions of said towing and steering elements, securing the same together in substantial parallelism, and adapted when relatively shifted to steer said elements with respect to the ship by which they are towed, and a barrier floated on edge in rear of the towing 115 elements.

5. Means for protecting ships against torpedo attack, comprising a series of towing elements at each side of the ship, disposed on edge in spaced apart relation, one 125 in advance of the other, and said two series extending rearwardly on divergent lines from the bow portion of the ship, means connecting the fore and aft portions of the members of each series in substantial paral- 130

lelism, means for relatively shifting the towing lines of each series to simultaneously change the angle made by a series of such members with respect to the towing ship, 5 and a barricade towed from each of said two series of members, each of said barricades being attached to its towing unit at a point inward from the outermost member of such unit.

10 6. Means for protecting ships against torpedo attack, comprising a series of bar-

riers floated on edge in spaced relation and disposed one in advance of the other, towing means connecting the forward and rearward portions of such barriers in substantial parallelism, means for relatively shifting said towing means to change the angles of such barriers with respect to a ship protected thereby and means for relatively inclining the barriers in the water. 15

LUCIUS E. WHITON.
